UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

ADDING MACHINE

1,416,363.

Specification of Letters Patent. Patented May 16, 1922.

Application filed September 20, 1919. Serial No. 325,096.

To all whom it may concern:

Be it known that I, HARRY LANDSIEDEL, a citizen of the United States, residing at Norwood, Hamilton County, and State of Ohio, have invented a new and useful Adding Machine, of which the following is a specification.

This invention relates to adding machines. Many, if not all, adding machines now 10 on the market include a main shaft, usually a rock shaft, which is turned in one direction to permit the adding mechanism and, in case the machine comprises recording mechanism, also to permit the recording 15 mechanism to operate. In the machines in which a rock shaft is used, the return movement of the rock shaft toward its starting point is utilized to restore certain parts of the machine to their starting points from 20 which they start to move or operate in the operations of the machine. During the first or initial portion of the movement of the rock shaft toward its starting point less power is required to actuate said shaft to 25 ward its starting point than is required during the final or last portion of the movement of the rock shaft toward its starting point. In the case of some of the machines now on the market, more power is needed 30 to actuate the rock shaft during the final or last portion of its movement toward its starting point because it is then that the rock shaft is required to overcome the resistance and inertia of some parts of the 35 machine and to move such parts to their proper positions for other operations, against the resistance of their actuating devices or springs.

The machines at present on the market are 40 not equipped with any mechanism to apportion the power applied to the rock shaft, whereby less power may be applied to the rock shaft during the first or initial portion of its movement toward its starting point than is applied to the rock shaft during the last or final portion of its movement toward its starting point. As a consequence 45 of the lack of appropriate mechanism for apportioning the power applied to the rock shaft during its movement toward its starting point, the rock shaft is actuated with 50 more power and more rapidly than is de-

sirable during the first portion of its return movement.

An object of the present invention is to 55 overcome the deficiencies mentioned, and others, and to provide a novel and efficient mechanism for use in adding machines and in other machines in which my invention may be satisfactorily employed which will 60 apportion power applied to any given part or mechanism such as the rock shaft of adding machines, so that the power will vary as needed.

Other objects will appear from the following description in which reference is made to the drawings and in which drawings:—

Fig. 1 is a view illustrating one embodiment of the invention applied to the main 70 shaft of a Dalton adding machine.

Fig. 2 is a plan view of the invention in connection with the main shaft and differential mechanism of a Dalton adding machine.

Fig. 3 is a side elevation illustrating the 75 position of the parts when the rock shaft is turned about one-half of the entire distance which it is required to turn from its starting point.

Fig. 4 is a side elevation illustrating the 80 positions of the parts when the rock shaft reaches the end of its movement from its starting point.

Fig. 5 is a side elevation showing the 85 positions of the parts when the auxiliary actuator or power increasing device functions to actuate or increase the power applied to the main shaft during the last or final portion of the movement of said shaft toward 90 its starting point.

The Dalton adding machine in which I have chosen to illustrate my present invention comprises a main rock shaft 1. The main shaft 1, as is well known, controls and 95 actuates the connections controlling the operation of the machine.

The machine comprises a set of numeral key levers 2 operable to set up numbers in the differential mechanism 3, after which the main shaft 1 is turned in one direction to permit the adding pinion actuators 4 to operate as required to actuate the adding pinions (not shown). The machine shown

also comprises recording devices 5 co-ordinated with the racks 4 for recording the numbers added and the totals thereof. The Dalton adding machine is manufactured under the Hubert Hopkins Patent, No. 1,039,130, dated September 24, 1912, and further description of the Dalton machine is unnecessary in connection with the present invention.

10 My invention comprises mechanism for apportioning the power to the shaft 1 as the power may be desired. As shown, an arm 6 is attached to the shaft 1, and an actuating spring 7 is connected with said arm 6 by means of a link 8 having one end connected with the spring 7 and its opposite end provided with a pivotal connection 9 with the arm 6. The rock shaft 1 may be turned from its starting point manually by 20 means of a lever 10, or otherwise, as desired. When the rock shaft reaches the limit or extent of its movement from its starting point it is released; whereupon the spring 7, which had been tensioned or energized 25 by and as an incident to the movement of the rock shaft from its starting point, functions to impart the initial or first portion of the movement of the rock shaft toward its starting point.

30 In the particular embodiment of my invention illustrated, less power is applied to the rock shaft during the first or initial portion of its movement toward its starting point than is applied to said shaft during the last or final portion of its movement toward its starting point. Obviously, however, these provisions may be varied within the scope of the invention and I do not restrict myself unessentially.

40 In the particular embodiment of the invention shown, the increase of power is applied to the shaft 1 by a spring 11 and mechanism arranged to co-operate therewith. One end of each of the springs 7 and 11 is connected to a stationary attachment. The opposite end of the spring 11 is pivotally connected with an angular lever 12, one end of which is pivoted on a support 13. The arm 6 is provided with an arcuate extension 45 50 55 60 65 70 75 80 85 90 95 100 105 110 115 120 125 130 135 140 145 150 155 160 165 170 175 180 185 190 195 200 205 210 215 220 225 230 235 240 245 their starting points. By reference to Fig. 5 it will be understood that the plate 16 is latched in its upper position during the last or final portion of its movement of the shaft 1 towards its starting point, and that when the time arrives for the roller 15 to engage the surface 28 the rear end of the plate 16 contacts with the lower end of the latch member 25 and disengages said latch member 25 from the device 26, leaving the lever 12 under control of the spring 11 and permitting the roller 15 to engage with the surface 28 of the plate 16. From this time on, the spring 11 acts upon the shaft 1 to increase the power applied to it during the time that said shaft is moving towards its starting point. Finally, at about the time that the shaft completes its movement toward its starting point, the upper branch of the latch member 20 contacts with the roller 15, thereby releasing the latch 20-21 and permitting the spring 24 to draw the plate 16 to its idle position shown in Fig. 1. In the idle or normal position the lever 12 may bear against a stud or roller 29, relieving the pressure of said lever from the connections on the shaft 1, and leaving the shaft 1 free to be started on its forward movement without resistance from the spring 11. From the foregoing it will be understood that my invention fully and satisfactorily serves its purpose. The forward movement of this shaft 1, as in the embodiment shown, may be utilized to energize the spring 11 by somewhat indirect force applied by the arcuate edge of the plate 16 against the roller 15. At the proper and desirable time, during the return movement of the shaft 1 toward its starting point, the power or energy thus stored up in the spring 11 enters into the equation and functions to assist the spring 7, or other actuator that may be employed, to complete the last or final movement of the shaft 1 toward its starting point during the time that the additional power is needed or desired.

Obviously, the invention is capable of many uses and the construction thereof may be widely varied without departure from the principle and scope of the invention as set forth in the appended claims. I do not restrict myself to unessential particulars, but what I claim and desire to secure by Letters Patent is:—

1. Mechanism of the character described, comprising a shaft rockable from and to a starting position, means for turning said shaft from its starting position, an actuator for turning the shaft toward its starting position, an additional actuator arranged to co-operate with the first-named actuator during a portion of the turning movement of the shaft, leaving the first-named actuator to turn the shaft independently of the second-named actuator for a portion of the

turning movement of the shaft, and means for constantly increasing the energy of said additional actuator during the entire movement of said shaft from its starting position. 70

2. Mechanism of the character described, comprising an element to be actuated from and to a starting position, an actuator for actuating said element through the full extent of movement of said element in one direction, an additional actuator arranged to co-operate with the first-named actuator during a portion of the movement of said element, leaving the first-named actuator to actuate said element independently of the second-named actuator for a portion of the movement of said element, and means for constantly increasing the energy of said additional actuator during the entire movement of said element from its starting position. 80 85

3. Mechanism of the character described, comprising a rock shaft to be turned from and to a starting position, an actuator for turning the shaft during the initial portion of its movement toward its starting position, an additional actuator arranged to co-operate with the first one during the final portion of the movement of the rock shaft toward its starting position, leaving the first-named actuator to turn the shaft independently of the second one during the initial movement of the rock shaft toward its starting position, and means for constantly increasing the energy of said additional actuator during the entire movement of said shaft from its starting position. 90 95 100

4. Mechanism of the character described, comprising an element to be actuated, an actuator for actuating said element through the full extent of movement of said element in one direction, an additional actuator arranged to co-operate with the first-named actuator during a portion of the movement of said element, leaving the first-named actuator to actuate said element independently of the second-named actuator for a portion of the movement of said element, means for constantly increasing the energy of said additional actuator during the entire movement of said shaft in one direction, and mechanism controlling the second-named actuator as required to enable the same to operate as aforesaid. 110 115

5. Mechanism of the character described, comprising a rock shaft to be turned from and to a starting position, an actuator for turning the shaft during the initial portion of its movement toward its starting position, an additional actuator arranged to co-operate with the first one during the final portion of the movement of the rock shaft toward its starting position, leaving the first-named actuator to turn the shaft independently of the second one during the mi- 120 125 130

5 tial movement of the rock shaft toward its starting position, means for constantly and continuously increasing the energy of said additional actuator during the entire movement of said shaft from its starting position, and mechanism controlling the second-named actuator as required to enable the same to operate as aforesaid.

6. Mechanism of the character described, 10 comprising a shaft to be turned from and to a starting position, means for turning said shaft from its starting position, an actuator for actuating said shaft toward its starting position arranged to be energized by the 15 turning of said shaft from its starting position, an additional actuator, means for constantly and continuously increasing the energy of said additional actuator during the entire movement of said shaft from its 20 starting position, and means for utilizing the energy of said additional actuator to actuate said shaft toward its starting position, and preventing said additional actuator from actuating said shaft during the initial 25 portion of the movement of said shaft toward its starting position.

7. In an adding machine, a rock shaft rockable from and to a starting position, an arm in connection with said shaft, a spring 30 connected with said arm for imparting initial movement to said shaft toward its starting position, an actuator independent of said spring, means for constantly and continuously increasing the energy of said 35 actuator as an incident to the turning of said shaft from its starting position, and mechanism preventing actuation of said shaft by said actuator during a portion of the movement of said rock shaft toward its 40 starting position and arranged to co-operate with said actuator to enable said actuator to actuate said rock shaft toward its starting position during a portion of the movement of said rock shaft toward said starting 45 position.

8. In an adding machine, a shaft, a spring 50 for actuating the shaft, through full extent of movement of said shaft in one direction, an additional spring arranged to co-operate with and assist said first-named spring to actuate said shaft during the final portion of the movement of said shaft, leaving the first-named spring to move the shaft alone during the first portion of the movement of said shaft, means for energizing said additional spring, and a latch device holding said additional spring energized until it is time for said additional spring to co-operate with and assist said first-named 55 spring.

9. In an adding machine, a rock shaft arranged to be turned from and to a starting position, an actuator, a cam operated by said shaft for energizing said actuator 60 by the turning movement of the shaft from

its starting point and leaving said shaft free from a part of the power from said actuator while said actuator is being energized, a latch device for effecting latching engagement between said actuator and said shaft to enable the actuator to turn the shaft, means for holding said latch device in latching position, and means for moving said latch device to unlatching position as an incident to movement of said shaft to 75 its starting position.

10. In an adding machine, a rock shaft arranged to be turned from and to a starting position, an arm on said rock shaft, a latch device supported by said arm, a spring, 80 a connection actuated by said arm for energizing said spring as an incident to the turning of said rock shaft from starting position, and an element on said arm for engaging said latch device after said shaft 85 has turned a portion of the distance toward its starting point to enable said spring to actuate said rock shaft.

11. In an adding machine, a rock shaft arranged to be turned from and to a 90 starting position, a spring, a lever connected with said spring, means for actuating said lever to energize said spring as an incident to the turning of said shaft from starting position, and a latch device arranged to be 95 engaged by said lever after said rock shaft has completed a portion of its movement toward its starting position to enable said spring to turn said shaft.

12. In an adding machine, a rock shaft 100 arranged to be turned from and to a starting position, a spring, a lever connected with said spring, a cam operated by the shaft for actuating said lever to energize said spring as an incident to the turning of 105 said shaft from starting position, a latch device supported by said shaft, and means for positioning said latch device for engagement by said lever to enable said spring to turn said shaft. 110

13. In an adding machine, a rock shaft arranged to be turned from and to a starting position, a spring, a lever connected with said spring, a cam operated by the shaft for actuating said lever to energize said 115 spring as an incident to the turning of said shaft from starting position, a latch device supported by said shaft, means for positioning said latch device for engagement by said lever to enable said spring to 120 turn said shaft, and means for disengaging said latch device from said lever after said shaft has been turned by said spring.

14. In an adding machine, a rock shaft arranged to be turned from and to a starting 125 position, a spring for actuating said rock shaft toward its starting position, mechanism for energizing said spring, a latch device, means for moving said latch device to latching position, and means whereby said 130

latch device and said spring will co-operate to actuate said shaft during the final movement thereof towards starting position, leaving said shaft free from the cooperative action of said latch device and spring during the initial movement of said shaft toward its starting position.

15. In an adding machine, a rock shaft arranged to be turned from and to a starting position, a spring for actuating said rock shaft toward its starting position, mechanism for energizing said spring, a latch device, means for moving said latch device to latching position, means whereby said latch device and said spring will co-operate to actuate said shaft during the final movement thereof towards starting position, leaving said shaft free from the cooperative action of said latch device and spring during the initial movement of the shaft toward its starting position, and means for moving said latch device to unlatching position after said spring has completed its work.

16. In an adding machine, a rock shaft arranged to be turned from and to a starting position, a spring for actuating said rock shaft toward its starting position, a device for energizing said spring during movement of said rock shaft from its starting position, and a latch device for effecting latching connection between said rock shaft and said spring after said rock shaft has moved a portion of the distance toward its starting point.

17. In an adding machine, a rock shaft arranged to be turned from and to a starting position, a spring for actuating said rock shaft toward its starting position, a device for energizing said spring during movement of said rock shaft from its starting position, and a latch device for effecting latching connection between said rock shaft and said spring after said rock shaft has moved a portion of the distance toward its starting point, and means for releasing the said latching connection before said rock shaft starts to move from its starting position.

18. In an adding machine, a rock shaft arranged to be turned from and to a starting position, an arm supported by said rock shaft, a spring connected to said arm arranged to be energized when said rock shaft is turned from its starting position and to impart initial movement of said rock shaft toward its starting position after said rock shaft completes its movement from starting position, an additional spring, a lever connected with said additional spring, a latch plate supported by said arm normally disengaged from said lever, means for moving said latch plate to position to be engaged by said lever, means for retaining said latch plate in said position to be engaged by said lever, and means for disengaging said latch plate from said lever.

19. In an adding machine, a rock shaft arranged to be turned from and to a starting position, an arm attached to said rock shaft, a lever, a spring in connection with said lever, a device engaged by said arm for moving said lever to energize said spring while said rock shaft is moving from its starting position, a latch member movable to and from position to engage said device, and means for supporting said latch member in position to be engaged by said device.

20. In an adding machine, a rock shaft movable from and to a starting position, a spring, a lever connected with said spring, a support for said lever, means for actuating said lever to energize said spring during movement of said rock shaft from its starting position, a latch for supporting said lever in the position to which it is moved as aforesaid, means for releasing said latch after said lever has moved a portion of the distance toward its starting point, and mechanism for using the energy of said spring to actuate said rock shaft after said latch has been released.

21. In an adding machine, a rock shaft movable from and to a starting position, a spring, a lever in connection with said spring, means actuated by the rock shaft during movement thereof from its starting position for moving said lever in a direction to energize said spring, a latch for holding said lever in position to relieve the power of said spring from said rock shaft during the initial portion of the movement of said rock shaft toward starting position, and mechanism whereby the power of said spring will be used to actuate the rock shaft during the final portion of the movement of said rock shaft toward its starting position.

22. In an adding machine, a rock shaft movable from and to starting position, a lever, a spring in connection with said lever, means for moving said lever in a direction to energize said spring as an incident to movement of said rock shaft from its starting position, a latch for holding said lever in position to retain the said spring energized and to prevent the energy of said spring from being exerted upon the rock shaft during the initial portion of the movement of said rock shaft toward its starting position, means for releasing said latch after said rock shaft has moved a portion of the distance toward its starting position, and elements whereby the energy of said spring will be exerted upon said rock shaft after said latch is released.

23. In an adding machine, a rock shaft movable from and to starting position, a lever, a spring in connection with said lever, means for moving said lever in a direction to energize said spring as an incident to movement of said rock shaft from its starting position, a latch for holding said lever in position to retain the said spring ener-

gized and to prevent the energy of said spring from being exerted upon the rock shaft during the initial portion of the movement of said rock shaft toward its starting position, means for releasing said latch after said rock shaft has moved a portion of the distance toward its starting position, elements whereby the energy of said spring will be exerted upon said rock shaft after 10 said latch is released, and means for controlling said elements.

24. In an adding machine, a rock shaft movable from and to a starting position, a lever, a spring in connection with said lever, a cam device actuated by the rock shaft for actuating said lever to position to energize 15 said spring as an incident to movement of said rock shaft from starting position, and mechanism for using the energy of said 20 spring to actuate said rock shaft toward its starting position.

25. In an adding machine, a rock shaft movable from and to a starting position, a spring, a lever in connection with said 25 spring, a cam device operated by the rock shaft for actuating said lever to energize said spring, a latch device for holding said lever in position to prevent the energy of 30 said spring from acting on said shaft during the initial portion of the movement of said shaft toward starting position, latching mechanism for using the energy of said 35 spring to actuate said shaft during the final portion of the movement of said shaft toward its starting position, and means for controlling said latch device and said latching mechanism to prevent the energy of said 40 spring from being exerted upon said rock shaft during the initial portion of the movement of said rock shaft toward its starting position.

45. 26. In an adding machine, a rock shaft arranged to be turned from and to a starting position, means for turning said rock shaft from its starting position, an actuator for actuating said rock shaft toward its starting 50 position after said rock shaft has completed its full extent of movement from its starting position, a spring for actuating said rock shaft for a portion of its movement towards starting position, a device for energizing 55 said spring during the movement of said rock shaft from its starting position, and a latch device for effecting latching connection between the said rock shaft and said spring after said rock shaft has been moved a portion 60 of the distance toward its starting point by said actuator.

27. In an adding machine, a rock shaft arranged to be turned from and to a starting position, means for turning said rock shaft 65 from its starting position, an actuator for

actuating said rock shaft toward its starting position after said rock shaft has completed its full extent of movement from its starting position, a spring for actuating said rock shaft for a portion of its movement towards 70 starting position, a device for energizing said spring during the movement of said rock shaft from its starting position, a latch device for effecting latching connection between the said rock shaft and said spring 75 after said rock shaft has been moved a portion of the distance toward its starting point by said actuator, and means for releasing said latching connection to enable the said rock shaft to move toward its starting position 80 while said latching connection is released.

28. In an adding machine, a rock shaft arranged to be turned from and to a starting position, means for turning said rock 85 shaft from its starting position, an actuator for imparting initial movement of said rock shaft toward its starting position after said rock shaft has stopped its movement from starting position, an arm supported by said 90 rock shaft, a spring connected to said arm arranged to be energized when said rock shaft is turned from its starting position, a lever connected with said spring, a latch plate supported by said arm normally disengaged from said lever, means for moving 95 said latch plate to position to be engaged by said lever, means for holding said latch plate in said position to be engaged by said lever, and means for disengaging said latch plate 100 from said lever.

29. In an adding machine, a rock shaft arranged to be turned from and to a starting position, means for turning said rock shaft to starting position, an actuator for 105 imparting initial movement of said rock shaft toward its starting position after movement of said rock shaft is stopped, a spring, a lever in connection with said 110 spring, means actuated by the rock shaft during movement thereof from its starting position for moving said lever in a direction to energize said spring, a latch for holding said lever in position to relieve power of 115 said spring from said rock shaft during the initial portion of the movement of said rock shaft from starting position, and mechanism whereby the power of said spring will be used to co-operate with said actuator in 120 actuating the rock shaft during the final portion of the movement of said rock shaft toward its starting position.

30. In an adding machine, a rock shaft movable from and to a starting position, means for moving said rock shaft from 125 starting position, an actuator for imparting initial movement of said rock shaft toward starting position after movement of said rock shaft from its starting position has stopped, a lever, a spring in connection with 130

said lever, means for moving said lever in a direction to energize said spring as an incident to movement of said rock shaft from its starting position, a latch for holding said lever in position to retain said spring energized and to prevent the energy of said spring from being exerted upon the rock shaft during the initial portion of the movement of said rock shaft toward its starting position, means for releasing said latch after said rock shaft has been moved by said actuator a portion of the distance toward its starting position, and elements whereby the energy of said spring will be used to co-15 operate with said actuator to actuate said rock shaft toward its starting position after said latch is released.

31. In an adding machine, a rock shaft movable from and to a starting position, 20 means for moving said rock shaft from starting position, an actuator for imparting initial movement of said rock shaft toward starting position after movement of said rock shaft from its starting position has 25 stopped, a lever, a spring in connection with said lever, means for moving said lever in a direction to energize said spring as an incident to movement of said rock shaft from its starting position, a latch for holding said 30 lever in position to retain said spring energized and to prevent the energy of said spring from being energized upon the rock shaft during the initial portion of the movement of said rock shaft toward its starting 35 position, means for releasing said latch after said rock shaft has been moved by said actuator a portion of the distance toward its starting position, elements whereby the energy of said spring will be used to co-operate 40 with said actuator to actuate said rock shaft toward its starting position after said latch is released, and means for controlling said elements to operate and co-operate as aforesaid.

45 32. In an adding machine, a rock shaft

movable from and to a starting position, a device for turning said rock shaft from its starting position, an actuator for actuating said rock shaft toward its starting position after movement of said rock shaft from its 50 starting position is stopped, a lever, a spring in connection with said lever, a cam device actuated by the rock shaft for actuating said lever to position to energize said spring as an incident to movement of said rock shaft 55 from its starting position, and mechanism for co-operating said spring and said actuator to actuate said rock shaft toward its starting position after said rock shaft has been moved a portion of the distance to- 60 ward its starting position by said actuator independently of said spring.

33. In an adding machine, a rock shaft movable from and to a starting position, means for turning said rock shaft from its 65 starting position, an actuator for actuating said rock shaft toward starting position after the said rock shaft has completed its movement from starting position, a spring, a lever in connection with said spring, a cam 70 device operated by the rock shaft for actuating said lever to energize said spring during the time that said rock shaft is moving from its starting position, a latch device for holding said lever in position to prevent the 75 co-operation of said lever and said actuator during the final portion of the movement of said rock shaft towards its starting position, latching mechanism for using the energy of said spring to co-operate with said actuator 80 to actuate said rock shaft during the final portion of the movement of said rock shaft toward its starting position, and means for controlling said latch device and said latching mechanism to prevent said spring from 85 co-operating with said actuator during the final portion of the movement of said rock shaft toward its starting position.

HARRY LANDSFEDDEL.
